DYEING SPINDLE

Harry W. Butterworth, Jr., Philadelphia, Pa., assignor to H. W. Butterworth & Sons Company, Philadelphia, Pa., a corporation of Pennsylvania

Application April 26, 1939, Serial No. 270,263

2 Claims. (Cl. 68—198)

This invention relates to dyeing spindles for package dyeing machines of the type which are commonly employed in such machines for supporting the yarn packages while pumping dyeing or conditioning materials therethrough.

The yarn packages are wound upon a perforated paper or metal tube and the spindles utilized in holding the same are so constructed that dye may be delivered through the perforated tube 10 and the yarn wound thereon. The types of spindles now in use are unsatisfactory in many respects, the principal objection thereto being that, due to their construction, they either interfere with the circulation, as in the case of perforated spindles which tend to screen the fibres from the liquor with the result that accumulated screenings clog the spindle and are difficult to remove therefrom, or fail to provide adequate support for the relatively fragile package tube, or 15 are inherently weak, so that it becomes impossible to utilize them for holding a plurality of yarn packages.

The purpose of the present invention is the provision of a spindle which will provide an adequate support for one or more packages, which will provide a maximum area for circulation of the dyeing liquid and at the same time include a construction which will avoid blocking of the perforations of the package tube to the greatest possible extent, which will not present rough surfaces to which lint contained in the dyeing fluid can cling and thus serve to impede circulation, and which may be so constructed that it will closely fit within the package tube and thus 25 serve to prevent collapse thereof.

These and other objects I attain by the construction shown in the accompanying drawing wherein, for the purpose of illustration, I have shown a preferred embodiment of my invention 30 and wherein:

Fig. 1 is a fragmentary sectional view of a dyeing machine employing spindles constructed in accordance with my invention;

Fig. 2 is a section on line 2—2 of Fig. 1; and 35 Fig. 3 is a section on line 3—3 of Fig. 2.

Referring now more particularly to the drawing, the numeral 10 designates a drum or header through which dye may be introduced; 11, spindles supported from the drum and having their 40 lower ends projecting thereinto and held in the wall of the drum by threaded bushings 12. Each spindle comprises a round bar 13 one end of which has a reduced threaded extension 14 for the reception of a retaining nut 15. The bar, 45 from a point immediately adjacent the reduced

extension to a point immediately adjacent its opposite end, is spirally grooved, as indicated at 16, these grooves being of uniform depth from points immediately adjacent their ends and having such end portions gradually tapered as indicated at 17. Such grooves can, obviously, be formed in the bar by a milling operation which gives to the flutes 18 thus formed a smooth and finished surface offering no impedance to the 5 passage of dyeing fluid.

The diameter of the bar is made such that it closely fits the interior of the perforated tube 19 upon which the yarn package 20 is wound. Bushing 12 is shrunk upon the outside of the bar at a point where the grooves 16 have attained 10 their full depth and is formed in its outer end with a groove 21 to receive the end of the adjacent yarn package tube 19 and the under surface of nut 15 is provided with a corresponding groove 22 to receive the outer end of the topmost yarn 15 package tube. These grooves, since the package tubes can closely fit against the surface of the flutes 18, must be disposed in alignment with the 20 periphery of the spindle.

Where a plurality of packages is placed upon 25 the spindle, the spacers 23 are provided for disposition between adjacent packages, such spacers comprising simply rings closely fitting the spindle and having grooves 24 at their ends for the 30 reception of the ends of the adjacent yarn package tubes. It will be obvious that by employing a solid bar of this type the completed structure has a central core of considerable strength so that a number of packages can be used on each 35 spindle. Due to the fact that the grooves are smooth-walled and have attained their full depth before the circulation passages thus formed meet any surrounding surface, there will be no tendency of lint to collect and thus tend to impede 40 flow through the spindle. Likewise, due to the fact that the grooves extend into the liquor zone and emerge gradually from the solid rod in which they are formed, there is no tendency of the lint and fibres in the liquor to collect against square 45 end zones such as are provided in the usual construction. Since the package tube will closely fit about the spindle and the support afforded is spiral, any tendency to collapse on the part of these tubes is eliminated. Due to the fact that the grooves are spiral and the outer edges of the 50 flutes are extremely narrow, there is little tendency to obstruct the openings of the package tube and this, in turn, permits the package tube to be more closely fitted to the spindle. It is 55 pointed out that if straight fluting is resorted to

there will be a decided tendency of the ribs to obstruct a straight line of openings in the package tube and, for this reason, package tubes heretofore have usually been made very loose fitting, which increases the tendency of the same to crush.

As the spindle is capable of some modification without departing from the spirit of my invention, I do not wish to be understood as limiting myself to the particular structure herein shown except as hereinafter claimed.

I claim:

1. A package holder for dyeing machines comprising a rod having spiral flutes, a threaded extension at one end of the rod, a cap engaged with said extension, the grooves of the rod terminating short of the ends thereof and having

their terminals of progressively decreasing depth, and a bushing fixed to and surrounding the rod at a point spaced from the opposite end of the rod where the grooves of the rod are of their full depth.

2. A package holder for dyeing machines comprising a fluted rod, the flutes of which terminate short of the ends thereof and have their terminal portions of progressively decreasing depth, a cap detachably engaged with the unfluted portion of one end of the rod and a mounting bushing secured to the rod adjacent the opposite end thereof and at a point such that its outer terminal surrounds the flutes at a point where they are of full depth.
